UNITED STATES PATENT OFFICE.

WALTER KROLL, OF BERLIN, GERMANY, ASSIGNOR TO SIEMENS & HALSKE AKTIEN-
GESELLSCHAFT, WERNERWERK, OF SIEMENSSTADT, NEAR BERLIN, GERMANY.

TELEPHONE SYSTEM.

Application filed July 31, 1926, Serial No. 126,252, and in Germany August 15, 1925.

The invention relates to telephone systems with automatic working, and especially to those, in which hunting switches are used for the last stage in the speaking routes of groups 5 of lines going in the same direction.

Arrangements are already known for such systems, in which the high value and low value calls are routed over separate connecting routes. These systems are therefore 10 provided with a separate setting and a speaking route for low value calls and a separate setting and a speaking route for high value calls.

Now the object of the present invention is 15 to set up the high value as well as the low value calls to groups of lines going in the same direction over the same connecting routes. This is achieved by providing the last numerical impulse receiver in the setting up 20 of the connection with testing devices, which enable calls of different value to be set up over the same connecting devices. These testing devices have their circuits so arranged that they only cause a non-numerical switch 25 located beyond the last number impulse receiving device to be positioned when over it lines can be reached that can be used for the call to be set up. Hence the non-numerical switch can only be started up when in setting 30 up a high value (trunk) call there is at least one outgoing line still free or is engaged by a low value call (local call), and the switch is only started up for making a low value call when there is at least one outgoing 35 line still free.

The drawings show by way of example of 40 the invention a telephone system in which local and trunk calls are set up over the same final selectors and line finders to a group of P. B. X. lines, which is larger than the number of contacts in a level of the final selector. The final selectors are provided with two means of access, one of which is reached for local calls over a group selector, while the 45 other is reached for trunk calls over a special trunk group selector. The invention is of course not limited to this example of carrying out the invention. Local as well as trunk calls could be set up in known manner over 50 the same kind of group selectors.

The Figure 1 shows a preselector VW, which is associated with a subscriber's line and over which can be reached a number of group selectors, for example the one designated 55 by I. GW. This group selector has access to

a final selector LW, which can also be reached over a trunk group selector FGW from an operator's position. The trunk group selectors FGW are connected to trunk preselectors FVW, which are associated with a junction 60 jack Vkl.

The Figure 2 shows a line finder NW, which is connected to a bank contact of the final selector LW, and to which are connected a number of exchange lines to a P. B. X. The 65 exchange lines going to the P. B. X. are arranged for both way working. Hence at the public exchange they terminate at contacts of the line finders as well as at preselectors, of these the Figure 2 shows the preselector 70 VW1 associated with the line VL.

The method of operating the arrangement shown in the Figures 1 and 2 will now be further described. For this purpose will first be described the setting up of a local 75 call to the line VL shown in Figure 2 going to the P. B. X. When the receiver is taken down at the subscriber's station N, the preselector VW is started up and in known manner it seizes an idle group selector, for example I. GW. When the wipers of VW reach the line going to the group selector I. GW the winding I of the relay C is energized over the test wiper of the preselector and over the off-normal contact 1k of the group selector. 80 At the same time the relays A and B are operated over the loop of the calling subscriber's line. The relay C locks itself over the following circuit: earth, contact 2c, winding II of relay C, contact 3a, winding of 85 V2, battery, earth. Furthermore, the relay C at its contacts 4c and 5c prepares the positioning and steering circuit for the succeeding final selector. The positioning of the group selector I. GW is effected by the release of the relay A in accordance with the 90 first train of impulses transmitted by the subscriber in known manner. After the group selector has been raised to the desired level, its wipers are rotated until an idle final selector, for example LW has been found. Thereupon the following test circuit is closed: earth, windings I and II of P, contact 6v2, test 95 wiper of I. GW, winding I of C1, wiper II of the side switch in position 1, battery, earth. 100 The relays P and C1 are energized in this circuit. The relay P short circuits its winding I of high resistance at its contact 7p, and at its contacts 8p and 9p it switches through 105 the speaking leads of the group selector I. GW 110

over the wipers to the speaking leads of the final selector LW. At the final selector the relay C1 at its contact 10c1 closes a locking circuit for its winding II in series with the 5 winding I.

If the calling subscriber now transmits the next train of impulses, the relay A falls back in accordance with the number of impulses, and each time it closes its contact 11a. At the 10 same time at each impulse the contact 3a is opened and the contact 12a is closed. The opening of the contact 3a removes the short circuit of the relay V1, the latter therefore operates and at its contact 13v1, it applies 15 battery to the lower speaking lead. At each impulse the closing of the contact a3 short circuits the winding of the relay V1, which therefore acts as a slow acting relay and it remains in the operated position for the whole 20 train of impulses. For the duration of the train of impulses the relay B1 is energized over the lower speaking lead in the following circuit: battery, contacts 13v1, 5c, 9p, wiper of I.GW, arm III of the side switch in position 1, 25 winding of relay B1, earth. The relay B1 opens its contact 14b1 and so prevents the side switch moving on after the first lifting step, whereupon the off-normal contact 18 K is closed. Each time an impulse is received at 30 the group selector the contact 11a is closed and over it the following circuit is established: earth, contacts 4c, 11a, 8p, wiper of I.GW, arm IV of the side switch in position 1, winding I of relay A1, contact 15w, resistance W2, 35 battery, earth. The relay A1 at its contact 16a1 closes a circuit for the lifting magnet HM over the arm V of the side switch in position 1. The lifting magnet HM raises the wipers of the final selector into the desired 40 level.

At the end of the lifting movement the relay V1 at the group selector I.GW falls back, because it remains short circuited for some time over contact 3a. It opens the contact 45 18v1 and so interrupts the circuit of the relay B1. The latter closes its contact 14b1, thereby establishing the following circuit for the motor magnet S of the side switch: earth, contacts 14b1, 17a1, arm I of the side switch 50 in position 1, off-normal contact 18k, winding of magnet S, battery, earth. The magnet S causes the arms of the side switch to move on into the position 2. In this position is closed the following circuit for the winding II of 55 relay J: earth, contacts 19c1, 20j, arm III of the side switch in position 2, winding II of relay J, battery, earth. The relay J closes its contact 21j before it can open its contact 20j. Therefore the winding III of the relay 60 J is energized over the following route: battery, winding III of J, contact 21j, side switch arm II in position 2, contact 19c1, earth. The windings II and III of relay J oppose each other on the core, hence the relay is not operated when both windings are simultaneously 65

energized. Hence the relay J falls back at once and cannot be again energized, because the side switch has in the meantime been moved into position 3 owing to the magnet S having energized over the arm I in position 2. 70 On leaving the position 2, the arm III opens the circuit of winding II of relay J. In position 3 the motor magnet S is energized over the back contact 22j and the side switch arm I, hence the arms reach the position 4. In this 75 position the same circuit is closed for the motor magnet S of the side switch over the arm I, so that it reaches the position 5. The following circuit for the relay A1 is now established: battery, resistance W2, contact 80 15w, winding of relay A1, side switch arm III in position 5, contacts 24 C1, 25h and 26p1, earth. The relay A1 is operated and closes over its contact 16a1 and the arm V of the side switch in position 5 a circuit for the rotary magnet DM, and energizes over the contact 27a1 the winding II of the slow acting relay U. The relay U is operated and by opening its contact 28u, it prevents the side switch moving out of the position 5. The rotary magnet DM is energized over the above 85 described circuit, and it brings the wipers of the final selector LW into contact with the first bank contacts of the selected level, and at contact 29dm it short circuits the relay A1. 90 The latter releases and at its contact 16a1 it opens the circuit of the rotary magnet DM. This at contact 29dm removes the short circuit from the winding of the relay A1, which is therefore again operated and again energizes the rotary magnet DM over the contact 95 16a1. The inter-action of the relay A1 and the rotary magnet DM causes the wipers to move step by step from one bank contact to the next until an idle line has been found going to an idle line finder. 100

If all the lines going in the same direction accessible over the line finder be engaged, the contact 70ga is closed as will be described below. Thereby when the relay A1 is operated for the first time a circuit for the relay H is established over the winding I and the contact 60a1. The circuit of relay A1 is opened at contact 25h, thereby preventing the further rotation of the final selector. The magnet S of the side switch is now energized over the contacts 14b1, 17a1, 28u1 and over the arm I in position 5. The side switch reaches position 6 and it cannot leave this position because the test relay P has not been operated. In this 115 position a busy signal is applied over the arm III to the windings II of A1 and B1, and the signal is induced in the windings I of these relays and thence to the calling subscriber. 120

Assuming, however, that the line finder NW shown in Fig. 2 is the first idle switch connected to the level of the final selector LW, the following test circuit is now established: earth, contacts 19c1, 30mk (closed upon the first rotary step of the switch), side switch 125 130

arm IV in position 5, windings I and II of relay P1, contacts 31a1, 32v3, test wiper LW, back contact 38t1 (Fig. 2), winding of relay R, contact 34g, battery, earth. The relays P1 and R are operated over the circuit. At its contact 26p1 the relay P1 opens the circuit for energizing the relay A1, hence the wipers of the final selector LW come to rest on the seized contacts, and at contact 35p1 the relay short circuits its high resistance winding I, thereby in known manner marking engaged the seized final selector. During the rotary movement of the final selector the relay U was maintained energized owing to the intermittent energization of relay A1; the interruption of the circuit over its winding II at contact 27a1 causes the relay U to fall back and at its back contact 28u it closes the following circuit for the motor magnet S of the side switch: earth, contacts 14b1, 17a1, 28u, side switch arm I in position 5, winding of the magnet S, battery, earth. The side switch reaches its position 6 and is then moved into position 7 owing to the energization of magnet S over the contact 36p1 and the arm I. In this position the circuit of the motor magnet S of the side switch is closed over the contact 80p1 and the arm I, hence the side switch reaches the position 8.

30 However, before dealing further with the circuit changes at the final selector LW, a description will first be given of the operations effected at the line finder NW (Fig. 2) owing to the energizing of the relay R over the above described testing circuit. When it operates, the relay R at the line switch NW closes the contact 37r, thereby energizing the rotary magnet as follows: earth, interrupter Un1, back contact 38t1, contact 37r, winding of the rotary magnet D, battery, earth. At contact 39r the relay R prepares the test circuit of the line finder. The rotary magnet D causes the wipers of NW to move on until an idle line has been found going to the wanted P. B. X. If the line VL shown in the Fig. 2 be idle, the following test circuit for the line finder NW is established: earth, winding I of relay T1, contact 39r, test wiper of NW, test lead of the preselector VW1, which is in its normal position and is associated with the line VL, windings I and II of the relay T2, battery, earth. Over this circuit are operated the relay T1 at NW and relay T2 at VW1. The relay T1 at its contact 33t1 opens the circuit of relay R and at contact 38t1 it opens the circuit of the rotary magnet D. Hence the line finder comes to rest on the bank contacts of the line VL. The relay T1 also switches through at its contacts 40t1 and 41t1 the speaking leads over the wipers of the line finder NW to the line VL, and it closes its contacts 42t1 and 43t1. Thereby the test lead coming from the final selector LW is at the contact 42t1 directly connected over the test arm of NW to the

windings of the relay T2 at the preselector VW1, and at the contact 43t1 the winding II of relay T1 is connected in parallel with relay T2 to the test lead. The circuit for energizing the relay T1 (winding I) is opened at contact 39r. At the preselector VW1 the relay T2 short circuits its high resistance winding I at its contact 44t2. It should be here mentioned that when the preselector VW1 is in its normal position, the relay X is continuously energized over the test wiper. When the line VL is taken into use over a line finder, the relay X is bridged by the low resistance winding of the test relay (P1) at the final selector, hence it falls back. The relay closes its contact 45a located in series with similar contacts at the preselector, these contacts being associated with exchange lines connected to the same line finder and being located in the circuit of the relay Y.

The relay Y serves to disconnect the line finder NW when all the exchange lines accessible over it are engaged. In that case at contact 46y is closed a circuit for the relay G over the back contact 47ga. At its contact 48g the relay G directly earths the test contact of the line finder in the bank of the final selector LW, so that its test relay P1 cannot be operated when the test wiper reaches this contact. When the lines of all the line finders NW accessible over the final selector LW are engaged, the relay GA is energized over the contact 49y and similar contacts of the cut-off relays Y belonging to other P. B. X. line groups. The relay GA at its contact 47ga opens the circuit of relay G and it closes the contact 50ga. The relay G opens the contact 48g and closes the contact 34g, hence the test circuit for the final selector LW is again prepared and the line finder NW can be again reached. When the line finder NW is taken into use in the manner above described, the relay R is energized and it now however closes the following circuit for the winding I of relay T1: battery, contact 50ga, resistance W1, contacts 51r and 39r, winding I of relay T1, earth. But this circuit is established only when the test wiper of NW stands on a contact that is not directly earthed. The object of this arrangement will be explained when describing the setting up of trunk calls.

During the position of the line finder, the side switch of the final selector has reached position 8 in the manner described above. In this position the motor magnet S is energized in the following circuit: earth, contacts 14b1 and 80p1, side switch arm I in position 8, winding of S, battery, earth. Hence the side switch reaches the position 9, in which the magnet S is again energized over the contacts 19c1 and 20j and over the arm I; the side switch therefore moves into the position 10. In this position the ringing current is transmitted from the source RQ over the arm III to the upper speaking lead and thence over

- the upper wiper and contact 40t1 to the exchange line VL and a calling signal at the P. B. X. and over the contact 41t1 to the lower speaking lead, which is earthed over 5 the side switch arm II of the final selector LW. In position 10 of the side switch the motor magnet S is energized over a slow interrupter LU and over the arm I, so that the side switch goes into the position 11. 10 When the contact 521 is closed, the source of ringing current RQ is connected over the arm III and a winding I of relay U to the exchange line VL. The contact 521 is controlled by a relay L, which is momentarily 15 energized over a time switch ZS once every 10 seconds. The relay U is so constructed that it only responds to direct current, hence it is not operated by ringing current over its winding I. During the ringing pauses the 20 contact 531 is closed, hence battery is directly applied over the winding I of relay U to the upper speaking lead. When the P. B. X. answers the call, the line loop of the exchange line VL is closed and the relay 25 U is operated by its winding I. The relay closes its contact 54u, hence the motor magnet S of the side switch is energized in the following circuit: earth, contacts 14b1, 17a1, 54u, arm I of the side switch in position 11, 30 winding of magnet S, battery, earth. The side switch reaches its position 12, in which the relays A1 and B1 are energized in the following circuit: earth, battery, resistance W2, contact 15w, winding of relay A1, side 35 switch arm III, wiper of LW, contact 40t1, arm of NW, upper lead of the line VL, which at the P. B. X. is connected to the lower speaking lead of this exchange line, middle wiper of NW, contact 41t1, middle wiper of 40 LW, side switch arm II, winding of relay B1, earth. The establishment of the connection at the P. B. X. can be effected in any desired manner.
- At the end of the conversation when the 45 connection is released at the P. B. X. the relays A1 and B1 at the final selector fall back, whereupon the side switch magnet S is energized over the following route: earth, contacts 14b1, 17a1, arm I in position 12, winding 50 of magnet S, battery, earth. The side switch therefore moves into the position 13. If in the meantime the calling subscriber N has also hung up his receiver the relays A and B have fallen back at the group selector LGW. At its contact 12a, the relay A short circuits the winding II of the relay C, which falls back after a little while and at its contact 2c opens the circuit of the relay V2. The latter at contact 6v2 opens the holding circuit over the windings I and II of relay P. The relay P at its contacts 8p and 9p opens the speaking leads at the group selector, while the relay C1 closes its contact 55c1, thereby energizing the side switch magnet S over the following route: earth, con-

tacts 56 b1, 57t, 55c1, side switch arm I in the position 13, winding of magnet S, battery, earth. The side switch reaches the position 14, in which the magnet S is energized in the same manner as in position 12 70 over arm I, and the side switch is moved into the position 15. The following circuit for the release magnet M of the final selector LW is now closed: earth, contact 58c1, arm I of the side switch, winding of the release magnet M, battery, earth. The magnet M in known manner returns the final selector to its normal position, in which the off-normal contact 59k is closed, hence the magnet S of the side switch is energized in parallel with the winding of the magnet M. The side switch reaches the position 16, in which the magnet S operates in the same circuit and the side switch is moved into its normal position. 85

Upon the release of the connection at the P. B. X. the release of the relay A1 at the final selector also opened the contact 60a1, hence the engaged condition is removed from the line finder and the line VL. The relays H, T1, T2 fall back and the relay X is again energized over the windings I and II of T2. At the line finder NW the relay T1 closes its contact 38t1, thereby closing the interrupter circuit for the rotary magnet of this switch over the arm d. The wipers of the line finder NW are now moved on until the arm d leaves its segment, whereupon the circuit of the rotary magnet D is opened and the switch has reached its normal position. The relay T2 removes the engaged condition from the preselector VW1 by closing the contacts 61t2 and 62t2, while the relay X opens its contact 55x in the circuit of the relay Y. 90

The setting up of an incoming trunk call to a P. B. X. line will now be described. In Fig. 1 is shown a cord circuit and a multiple jack VKl forming part of the connecting devices at the position FPl of a trunk operator. In order to set up a toll call, the operator inserts the plug St of an idle cord circuit into an idle jack such as VKl. This starts up the trunk preselector FVW indicated in Fig. 1 and it takes into use an idle group selector FGW. Having operated a key WS, the operator actuates her number dial, of which only the contacts n, s1 and s2 are shown. The trunk group selector FGW can be positioned in known manner by the first train of impulses and it then hunts for an idle succeeding switch for example final selector LW. At the latter, the relay C1 is energized over the test lead, and at contact 10c1 closes a locking circuit for its windings I and II. When the trunk operator transmits the next train of impulses, the relay A1 is energized by each impulse over the plug St, jack VKl, upper speaking lead at the trunk preselector and trunk group selector and over the side switch arm IV in the position 1. The relay

repeats the received impulses to the lifting magnet HM over the contact 16a1 and the magnet sets the final selector onto the desired level. At the end of the train of impulses the contact *n* at the trunk position FPl is opened, thereby at the final selector releasing the relay B1, which was energized over the contact *n* and the lower speaking lead during the train of impulses. Over the contacts 14b1, 17a1 and 18k is established a circuit for the side switch magnet S. The side switch goes into position 2. Now for trunk calls an additional impulse is transmitted after the end of the impulse transmission. This is effected by closing the contact *s2* at the trunk position; winding I of the relay J is thereby energized over the arm IV of the side switch in position 2. At the same time over the contact 19c1 and the back contact 20j is established a circuit for the winding II of the relay J, which closes a circuit for its winding III over its contact 21j and the side switch arm II in positions 2 to 4. The relay J having been energized in position 2 of the side switch by its winding I, it remains energized in position 3 over its contact 21j and the side switch arm II. The side switch is at once moved from position 2 into position 3, because its magnet S is energized over the arm I. But the contact 22j is now open, hence for the present side switch remains in this position. For the purpose of initiating the test, the trunk operator presses her test key PT, and thereby battery is applied to the lower speaking lead and the relay B1 at the final selector LW is energized over the arm III of the side switch. At its contact 63b1, the relay B1 locks itself over the following route: earth, winding of B1, side switch arm IV, contacts 63b1, 64t and 65p1, winding of relay V3, contact 15w, resistance W2, battery, earth. The relay V3 is also energized in this circuit, hence the following circuit is established for the magnet S of the side switch: earth, contacts 66b1, 67v3, 68v3, arm I in position 3, winding of magnet S, battery, earth. The side switch reaches the position 4, in which the rotary magnet DM is operated in parallel with the side switch magnet S in the circuit that has just been described. At the same time the relay V3 has closed its contact 69v3, thereby connecting the winding I of relay H to the test wiper of the final selector LW. The rotary magnet now brings the wipers of the final selector LW onto the first contact of the selector level. The test wiper of the final selector reaches a preliminary test contact, which is connected to battery over the contact 70ga when all the line finders connected to the selected level are engaged. In that case the relay GA is energized in the manner already described. The winding I of relay H, which is connected to the test wiper, is then energized. The relay H is oper-

ated, and at its contact 71h it closes a locking circuit for its winding II, which extends over contact 19c1 to earth. In the meantime the side switch has reached the position 5. At its contact 71dm the rotary magnet DM shunts the winding of relay V3 by a low resistance W3, hence the relay falls back after a little while, and interrupts the circuit of the rotary magnet DM at contact 67v3. Furthermore, in position 5 the short circuit is removed from relay T at the arm II, hence the relay is operated in series with the winding III of relay J over the contact 72j and the multiple contact 30mk if the test wiper of the final selector LW reaches an idle or a locally engaged line finder. If the line finder be engaged by a trunk call, earth is directly applied to the test contact, hence the winding of relay T is short circuited over the test wiper, the contacts 32v3, 31a1, 73h, side switch arm II in position 5, contact 21i, and it can therefore not operate. At its contact 71dm, the rotary magnet DM now opens the short circuit of the winding of relay V3, which therefore operates and again closes the circuit of the rotary magnet DM at contact 67v3. The interaction between the relay V3 and the rotary magnet DM continues until a locally engaged line finder has been found. Thereupon the relay T is operated, because its winding is no longer short circuited, and at contact 64t it opens the circuit of the relays V3 and B1. These relays fall back and the relay V3 at its contact 67v3 opens the circuit of the rotary magnet DM, while the relay B1 at its contact 14b1 closes a circuit for the motor magnet S of the side switch, which extends over the contacts 17a1 and 28u and over the arm I of the side switch. In position 6 of the side switch, the magnet S is energized over the contacts 56b1, 74t and over the arm I, and it moves the side switch into position 7. It remains in this position and transmits the local busy tone over arm III to the trunk operator. The latter can then communicate with the local subscriber because the speaking leads are available for conversation over the condensers C2 and C3 and over the contacts 75t and 76t. The subscriber is notified that the local connection will be released. To do this, the operator presses the release key TT, thereby applying earth to the upper speaking lead and energizing the relay G1 over the contacts 77t and 78a1. At its contact 79g1 the relay G1 closes the following circuit for the magnet S of the side switch: earth, contacts 56b1, 74t, 79g1, arm IV in position 7, winding of magnet S, battery, earth. The side switch goes into position 8, in which earth is applied to both speaking leads over the arms III and IV and over the contacts 75t and 76t, thus in known manner releasing the existing local connection. The relay PI can then operate over the test wiper of the

final selector LW and over the side switch arm V, and closes its contact 80p1. Thereby the magnet S is energized over the contact 14b1 and the arm I of the side switch, hence 5 the side switch goes into the position 9, in which it remains until the end of the trunk conversation. Over the contact 81i and over the arm II the P1 is short circuited and earth is directly applied to the test contact of the 10 line finder used. The line finder remains on the contact it used for the local call hence the trunk operator can at once connect up the ringing current. For this purpose she presses the key PT, over which battery is applied 15 to the lower speaking lead and the relay Q is energized over the contacts 82t and 83b1. The relay Q closes its contacts 84a, which apply ringing current to the exchange line taken into use over the following circuit: 20 battery, source of ringing current RQ, contacts 86g1 and 84g, side switch arm III, contact 75t, upper speaking lead LW, contact 40t1, at NW, upper speaking lead of the line VL, ringer at the P. B. X., lower speaking 25 lead of the exchange line VL, contact 41t1, lower speaking lead of LW, contact 76t, side switch arm IV, contact 85q, earth. To stop the ringing current the operator returns the key PT to its normal position, the relay Q 30 therefore falls back, at its contacts 84q and 85q it disconnects the ringing current and at its back contacts 87q and 88q it establishes the speaking circuit. When the P. B. X. answers the call, the relays A1 and B1 are energized, but this has no effect for a trunk call. 35

The release of the trunk connection is controlled by the supervising trunk operator. The withdrawal of the plug St from the jack VK7 in known manner causes the release of 40 the trunk group selector FGW, which interrupts the blocking circuit for the final selector LW, hence the relay C1 falls back. The latter at contact 19c1 opens the locking circuit of the relays J and T. The relay T 45 at its contact 57t closes the following circuit for the release magnet M of the final selector LW: earth, contacts 56b1, 57t, 55c1, arm V in position 9, winding of the release magnet M, battery, earth. The release magnet in 50 known manner causes the final selector LW to return to its normal position, in which the cff-normal contact 59k is closed, and the magnet S of the side switch is thus energized in parallel with the release magnet M. The 55 side switch reaches the position 10, and the energizing of magnet S over the slow interrupter LU and the arm I causes it to go into position 11. In this position the magnet S is energized over the contacts 56b1, 57t, 55c1 and over arm I and it brings the side switch into position 12. In this position the circuit of the magnet S extends over the contacts 14b1, 17a1 and over the arm I, hence 60 the side switch goes into position 13. It is re-

turned to its normal position through the positions 14, 15, 16 in the manner described above. 65

When the trunk operator initiates the test, if there be free outgoing lines from the line finders of the selected level, the relay H cannot be operated after the contact 69v3 has been closed, because the contact 70ga is open, and the relay T remains short circuited in the positions 4 and 5 of the side switch. In the position 5 of the side switch the short circuit extends over the contact 21j, arm II and over the back contact 89h. The alternate action of the relay V3 and the rotary magnet DM continues until the relay P is operated by the test arm of LW reaching an idle outgoing line. Thereupon it opens the contact 65p1, whereby the circuit for the relays B1 and V3 is opened. The remainder of the circuit changes are similar to those described above for the setting up of a local call. 80 85

When a call is originated from the P. B. X. over the line VL, the windings I and II of relay R1 are energized at the preselector over the contacts 61t2 and 62t2. At contact 90r the following circuit is closed for the rotary magnet D1: earth, interrupter Un2, contacts 91t2, 90r, winding of D1, battery, earth. The preselector VW1 is started up and in known manner it takes into use an idle group selector of the public exchange. When the test wiper of VW1 leaves its normal position, the test lead connected to the line finder NW is interrupted, the exchange line VL therefore cannot be taken into use by the line finder NW. At the same time, the relay X falls back and its contact 45x closes a point in the circuit of the cut-off relay Y. When the wipers reach an idle group selector, the relay T2 is energized over its windings I and II, and at its contact 91t2 it opens the interrupter circuit of the rotary magnet D1, at contact 44t2 it short circuits its high resistance winding I and at the contacts 92t2 and 93t2 it switches through the incoming line to the speaking leads going to the group selector. The remainder of the setting up of a call over the switches in the public exchange takes place in known manner, so it need not be described here. 100 105 110 115

What is claimed is:

1. In a telephone system, a combination toll and local rotary connector for use by an operator or local subscribers, a group of private branch exchange lines, non-numerical switches having access to said lines, means for operating said connector to select one of said non-numerical switches, and means responsive to said selection for operating said non-numerical switch to connect with one of said lines. 120 125

2. A telephone system as characterized by claim 1 in which, means is provided for preventing the seizure of a non-numerical switch

unless at the time it is tested one or more of the lines to which it has access are available for handling the call.

3. A telephone system as characterized by
5 claim 1 in which means is provided for preventing the seizure of a non-numerical switch for a local call unless at the time it is tested one or more of the lines to which it has access are idle, and for preventing the seizure of a non-
10 numerical switch for a toll call unless at the time it is tested one or more of the lines to which it has access are either free or are engaged in local calls.

4. A telephone system as characterized by
15 claim 1 which includes a switching means which is operated when all the lines in said group are busy for rendering the driving means of said connector non-operable for extending a local call.

20 5. A telephone system as characterized by claim 1 which includes a test relay in said non-numerical switch which is independent of the testing devices in said connector.

6. A telephone system as characterized by
25 claim 1 which includes a test relay in said non-numerical switch which is independent of the testing devices in said connector, and means controlled by said test relay for directly connecting the test wiper of said connector to the
30 test lead of said connected line.

7. In a telephone system, a group of branch exchange lines divided into subgroups, a plu-

rality of non-numerical switches each having access to a different subgroup, a combination toll and local rotary connector for use by an operator or local subscribers having access to said non-numerical switches, means for operating said connector to select one of said non-numerical switches, means responsive to said selection for operating said non-numerical switch to connect with one of said lines, means operated when all the lines in one of said subgroups are busy for rendering the associated non-numerical switch non-selectable from said connector, and means operated when all the lines in all the subgroups are busy for again rendering said non-numerical switch selectable if said connector has been taken into use by an operator.

8. In a telephone system, a combination toll and local connector, a second switch accessible to said connector, a line, means for operating said second switch to connect with said line, and means for operating said connector when used as a local connector to seize said second switch providing it is not connected to said line, and for operating said connector when used as a toll connector to seize said second switch under certain conditions irrespective of whether or not said switch is connected to said line.

In witness whereof, I hereunto subscribe my name this 5th day of July, A.D. 1926.

WALTER KROLL.
